G. J. Baker

WITNESS:

UNITED STATES PATENT OFFICE.

HARRY HEADING, OF HANGING ROCK, OHIO.

ENVELOPE.

1,421,227.

Specification of Letters Patent. Patented June 27, 1922.

Application filed April 18, 1921. Serial No. 462,189.

To all whom it may concern:

Be it known that I, HARRY HEADING, a citizen of the United States, residing at Hanging Rock, in the county of Lawrence 5 and State of Ohio, have invented new and useful Improvements in Envelopes, of which the following is a specification.

This invention relates to stationery, particularly to envelopes, and has for its object 10 the provision of an envelope provided with means whereby it may be opened easily and without the employment of a letter opener or other implement.

An important and more specific object is 15 the provision of an envelope within one end of which is secured a wire or other flexible member so that when one corner is torn off the envelope the entire end will be opened.

An additional object is the provision of 20 an envelope of this character which will be simple and inexpensive in manufacture, highly efficient in use, durable in service, and a general improvement in the art.

With the above and other objects and 25 advantages in view, the invention consists in the details of construction to be hereinafter more fully described and claimed and illustrated in the accompanying drawings in which—

30 Figure 1 is an elevation of an envelope constructed in accordance with my invention with the tearing wire shown in dotted lines,

Figure 2 is a cross sectional view through 35 the end of the envelope equipped with the wire,

Figure 3 is a detail sectional view at right angles to Figure 2,

Figure 4 is a perspective view of one of 40 the metallic members prior to its insertion within the envelope, and

Figure 5 is a view of the blank from which the metallic member is formed.

Referring more particularly to the drawings, the letter A designates an envelope of ordinary construction. In carrying out my invention I provide a metallic member 10 disposed in the opposite corners at one end of the envelope and this metallic member 50 is formed from a single sheet of metal 11 having its ends cut to provide tongues 12 and 13, 12 being the central tongue. This blank is bent transversely to provide a bight portion 14 and the outer tongues 13 are bent 55 to extend at right angles to the body, as

clearly shown in Figure 4. The numeral 15 designates the tearing or opening wire which has its ends bent around the bight portions 14 of the metallic members and it is of course apparent that the length of this wire 60 must depend upon the width of the envelope.

In applying my invention to an envelope the metallic members are inserted in one end of the envelope and the tongues 13 are 65 pressed through both sides of the envelope and are subsequently mashed flat, as shown in Figures 1 and 3. This will of course hold the parts in proper position. It may be desired, and in fact is preferable, to provide 70 a legend on one corner of the envelope adjacent one metallic member, the legend reading "Pull here with thumb and finger." It is of course apparent that some other similar direction might be printed upon the envelope if preferred. 75

In order to open an envelope constructed in accordance with my invention it is merely necessary that the operator grasp one corner of the envelope with his thumb and forefinger engaging opposite sides of the metallic member and then pull. This will result in tearing off one corner, including the metallic member, and a continued pull will cause the wire 15 to tear open the entire end 85 of the envelope.

From the foregoing description and a study of the drawings it will be apparent that I have thus provided a simply constructed and consequently inexpensive envelope which may be very quickly and easily 90 opened without danger of tearing the contents.

While I have shown and described the preferred embodiment of my invention it is 95 of course to be understood that I reserve the right to make such changes in the form, construction and arrangement of parts as will not depart from the spirit of the invention or the scope of the subjoined claims. 100

Having thus described my invention, I claim:

1. In an envelope, opening means comprising a pair of metallic members disposed within and having penetrating engagement 105 with the envelope at opposite corners of one end thereof, and a wire member disposed within said end and having its ends connected with said metallic members.

2. In an envelope, opening means comprising 110

ing a pair of metallic members each formed as a resilient strip bent upon itself transversely and having its ends slit to define tongues, a plurality of the tongues being bent to extend at right angles to the strip, said metallic members being disposed within the corners at one end of the envelope

with said right angularly extending tongues passed through the envelope and subsequently mashed down, and a wire member 10 having its ends connected with the bent portions of said metallic members.

In testimony whereof I affix my signature.
HARRY HEADING.
